Primary Examiner — T Chase Nelson*Assistant Examiner* — Kelly L Gross(74) *Attorney, Agent, or Firm* — Scully, Scott, Murphy & Presser, P.C.(57) **CLAIM**

The ornamental design for a controller for endoscope, as shown and described.

DESCRIPTION

FIG. 1 is a front perspective view of a controller for endoscope showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines in the drawings show portions of the controller for endoscope that form no part of the claimed design.

1 Claim, 7 Drawing Sheets(56)
